UNITED STATES PATENT OFFICE.

STEPHEN SZUCS, OF HOMESTEAD, PENNSYLVANIA, ASSIGNOR OF ONE-THIRD TO
ANDREW DUDAS, OF HOMESTEAD, PENNSYLVANIA.

SPINNING TOP.

1,419,651.

Specification of Letters Patent. Patented June 13, 1922.

Application filed September 8, 1921. Serial No. 499,259.

To all whom it may concern:

Be it known that I, STEPHEN SZUCS, citizen of the United States, residing at Homestead, in the county of Allegheny and State 5 of Pennsylvania, have invented certain new and useful Improvements in Spinning Tops, of which the following is a specification.

This invention relates to spinning tops, and it has for an object to provide a novel 10 type of top provided with means for making certain sounds as it spins, which sounds may simulate those made by an animal, for instance a dog, or any other animal that may be desired.

15 For further comprehension of the invention, and of the objects and advantages thereof, reference will be had to the following description and accompanying drawings, and to the appended claims in which 20 the various novel features of the invention are more particularly set forth.

Fig. 1 of the drawings is a perspective view of a top constructed according to the invention.

25 Fig. 2 is an axial sectional view thereof.

Fig. 3 is a vertical section at right angles to Fig. 2 and taken along the line 3—3 of the latter figure.

As here shown my improved top comprises 30 a hollow body 10 of roughly prolated spheroidal form which is flattened at its lower end as at 11. Fixed to this lower end in any suitable manner is a peg 12 which is co-axial to the body 10 and has a pointed lower end 35 13 upon which the top spins.

Within the body of the top is located air 40 blast mechanism, while the upper end 14 of the top is preferably formed to simulate the head of an animal, in the present case the head of a dog, through which the air blast is directed in a manner to produce the desired sound, such as that of the dog barking.

As here shown the air blast mechanism 45 comprises a bellows device consisting of a pair of face-boards 15 and 16, and a collapsible bag member 17. From one face of this bellows device a tube 18 leads to the head 14. The face-board 15 is pivotally attached to a shaft 19, fixed in the body 10, the face-board 16 being fixed at one end to this shaft 19.

To operate the bellows I provide a helically coiled power spring 20 which loosely surrounds a drum 21 fixed on a shaft 22 suit-

ably journaled in the body 10. Fixed to 55 one end of the shaft 22 is a ratchet wheel 23 to which one end of the spring 20 is attached, a spring pressed pawl 24 engaging this ratchet wheel to prevent backward movement thereof. Shaft 22 has fixed thereto a 60 projecting handle 25 for winding up the spring 20.

The opposite end of the spring is fixed to a gear 27 loose on the other end of shaft 22 and meshing with a pinion 28 fixed on a 65 shaft 29 suitably journaled in the body 10. Fixed to this shaft 29 is a gear 30 meshing in turn with a pinion 31 fixed on a shaft 32 having a crank element 33 formed thereon midway between its ends. This crank element 33 engages in a slot 34 formed in a plate 35 fixed to the bellows board 15 whereby the bellows is operated.

To spin the top the latter is placed on a flat base 40 in which is a suitable aperture 75 40' to receive the peg 12, a small passage 41 leading horizontally through the base from one side thereof to this aperture. A cord 42 passes through this passage 41 and is adapted to be wound in the usual manner 80 around peg 12, this cord having a handle 43 on its outer end. The base 40 is preferably provided with a handle 40'.

To hold the bellows against operation, preliminary to the spinning of the top, the face 85 plate 15 has an inverted T-bar 45 projecting downward therefrom through a suitable slot 46 formed in the bottom 11 of the body 10 and the top of the peg 12. When the top is in position on the base 40 the horizontal element of the T-bar will engage one wall of the aperture 40' and thus prevent oscillation 90 of the bellows board 15.

It is believed that the manner of operation and use of my improved top will be apparent from the above description, the top rising when the string 42 is pulled until the peg 12 clears the base 40, the top falling on the floor or other desired surface and continuing to spin. As the top rises the T-bar 100 45 is released from engagement with the wall of aperture 40' allowing the bellows to operate under the influence of spring 20.

As will be apparent, I may place any desired sound emitting device on the top, or 105 make various other changes or modifications, without departing from the principle of the invention.

Having thus described my invention what I claim as new and desire to protect by Letters Patent of the United States is as follows:

5. 1. A top comprising a hollow body, and means in said body for discharging a blast of air therefrom, said means including a bellows device, and power mechanism for operating said bellows device.
10. 2. A top comprising a hollow body, a bellows device in said body, a power spring in said body, and an operative connection between said power spring and bellows device.
15. 3. A top comprising a hollow body, a bellows device in said body, a power spring in said body, and an operative connection between said power spring and bellows device, said aperture connection comprising a slotted plate fixed to said bellows device, a shaft 20 having a crank element engaging in the slot

in the plate, a power spring and a multiplying gear connection between the spring and shaft.

4. A top comprising a hollow body, a peg fixed to the bottom thereof, a bellows device in said body having an oscillatory face-board, and a member projecting downwardly through the bottom of the body into a slot in the said peg, for the purpose specified. 25

5. A top comprising a hollow body, a peg fixed to the bottom thereof, a bellows device in said body having an oscillatory face-board, and a member projecting downwardly through the bottom of the body into a slot in the said peg, for the purpose specified, said member comprising an inverted T-bar. 30 35

In testimony whereof I have affixed my signature.

STEPHEN SZUCS.
